By Mr. & Mrs. Bell

UNITED STATES PATENT OFFICE

HERBERT M. FIGG, OF CEDAR RAPIDS, IOWA, ASSIGNOR TO CHERRY-BURRELL CORPORATION, OF CEDAR RAPIDS, IOWA, A CORPORATION OF IOWA

CHURN

Application filed June 9, 1930. Serial No. 460,042.

This invention relates to churns and more particularly to the shelves of churns and the salient object is to provide a novel manner for supporting the shelf or shelves in a churn 5 without the employment of any metal interior of the churn.

An ancillary object of the invention is to support the shelf in a manner which will permit easy removal and replacement there- 10 of.

A selected embodiment of the invention is illustrated in the accompanying drawing, and therein

Fig. 1 is a longitudinal sectional view of a 15 typical churn having my invention associated therewith;

Fig. 2 is a sectional view taken substantially on the line 2—2 of Fig. 1; and

Fig. 3 is a sectional view taken substan- 20 tially on the line 3—3 of Fig. 2.

In the drawing wherein a selected embodiment of my invention is illustrated in connection with a typical churn, 4 indicates the drum of the churn which embodies heads 5 25 and 6 suitably secured at the ends of the drum 4. A spider 7 is secured to the head 5 and is connected to and supported by a suitable driving mechanism generally indicated by 8. A spider 9 is secured to the head 6 and embodies a spindle journaled in the bearing 10 in the standard 11, the standard 11 and the housing of the driving mechanism 8 being mounted on the floor or other suitable support. It is customary to provide so-called 35 shelves in a churn and these shelves have in the past been supported by suitable metal brackets. The disadvantages of the metal brackets were many as will be readily apparent to anyone skilled in the art and I have 40 therefore provided an arrangement which obviates the necessity of employing such metal brackets. Usually one or more shelves are arranged in diametrical position in the drum of the churn but for the purpose of 45 description I will describe the mounting of but one of these shelves indicated by 12, it being understood that the other shelves are mounted in an identical manner. In the inner face of the head 5 I provide a recess 13 50 of a size substantially equal to the cross-sec-

tional area of the shelf 12 and of a similar shape which in effect provides a mortise and the end of the shelf 12 may be seated thereinto as a tenon and manifestly such an arrangement provides a secure support for one 55 end of the shelf. In order to arrange this end of the shelf in the recess 13 it is manifest that the shelf must be passed axially into the drum and I therefore provide in the head 6 an opening 14 which is aligned with the recess 13. This opening 14 is also of a size substantially equal to and of a shape similar to the cross section of the shelf 12. The shelf may therefore be passed through the opening 14 and one end thereof disposed in the recess 65 13, the opposite end being disposed in the opening 14, preferably with the end slightly inward of the face of the head. The outer face of the head 6 about the opening 14 is recessed as indicated at 15 in order that a 70 plate 16 may be disposed in this recess with the face of the plate flush with the face of the head 6, this plate being secured in position by the screws 17.

It is manifest from the foregoing descrip- 75 tion that the shelf of a churn may be securely retained in position and it is also apparent that the shelf may be readily removed and replaced when so desired by merely removing the plate 16. This plate 16 not only holds 80 the shelf in position but also prevents passage to and from the interior of the drum thus preventing leakage of the butter from the churn and entrance of foreign matter thereinto. 85

While I have illustrated and described a selected embodiment of my invention it is to be understood that this is capable of variation and modification and it also may be used to retain one or more shelves in a churn in 90 any desired relationship without departing from the purview of the following claims.

I claim:

1. A churn including a drum embodying oppositely disposed heads, a shelf, one of said 95 heads having a recess in the inner face thereof, the other of said heads having an opening therein through which said shelf may be passed whereby one end thereof may be disposed in said recess 100

with the other end thereof in said opening, and means for preventing displacement of the last named end of said shelf from said opening to retain the other end of said shelf in said recess.

- 5   2. A churn including a drum embodying oppositely disposed heads, a shelf, one of said heads having a recess in the inner face thereof of a size substantially equal to the cross-sectional area of said shelf, the other of said heads having an opening therein in alinement with said recess and of a size substantially equal to the cross-sectional area of said shelf whereby said shelf may be passed through said opening into said drum to dispose one end thereof in said recess with the other end thereof in said opening, and means for preventing displacement of said last named end of said shelf from said opening to retain the other end of said shelf in said recess.
- 10   15. 3. A churn including a drum embodying oppositely disposed heads, a shelf, one of said heads having a recess in the inner face thereof of a size substantially equal to and of a shape substantially similar to the cross section of said shelf, the other of said heads having an opening therein in alinement with said recess and of a size substantially equal to and of a shape substantially similar to the cross section of said shelf whereby said shelf may be passed through said opening into said drum to dispose one end thereof in said recess with the other end thereof in said opening, a plate disposed over the outer end of said opening, and means for securing said plate in position to prevent displacement of said shelf from said opening and to close said opening thus retaining the other end of said shelf in said recess.
- 20   25. 30. 35.
